UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CHAIN ATTACHMENT.

1,103,760.

Specification of Letters Patent. Patented July 14, 1914.

Application filed June 20, 1913. Serial No. 774,929.

To all whom it may concern:

Be it known that I, GILBERT W. GOODRIDGE, a citizen of the United States of America, and residing at Bridgeport, in the 5 county of Fairfield and State of Connecticut, have invented a certain new and useful Improvement in Chain Attachments, of which the following is a specification.

My invention relates to chain attachments 10 and particularly to an attachment for facilitating the adjustment of the length of the pull chains commonly used in connection with the pull switches of electric lamp sockets and the like, the object of my invention 15 being to provide a simple device of this character which is economically manufactured and efficient in operation.

In the accompanying drawing, Figure 1 is an elevation of an exemplary embodiment 20 of my invention arranged in a switch chain and partly detached; Fig. 2 is an end view thereof of the attachment alone, drawn to a larger scale; Fig. 3 is a perspective of the attachment showing a chain end in process 25 of adjustment; Fig. 4 is a plan of the blank for the attachment shown in Fig. 1.

It is frequently desirable to add to the length of the pull chains of standard make which are attached to sockets as sent out by 30 the manufacturer, since the standard length adopted may not bring the chain end within convenient reach where the socket is installed at a considerable height from the floor. It is often desirable furthermore to 35 shorten the chain, especially for desk lamps where the standard length chain brings the chain end below a point at which it is desirable to have it depend from the socket.

At present the customary manner of altering 40 the length of the chain necessitates the opening of the socket and the removal of the chain from the switch mechanism and the adjustment of either a shorter or longer chain in the chain rail. For the inexperienced this is an inconvenient and even dangerous operation.

The present invention provides an attachment by means of which the chain may be 45 readily adjusted in length by the inexperienced purchaser, as well as by the skilled electrician, without opening the socket.

In the form shown, the present attachment comprises a cylindrical body 10 formed of thin spring metal apertured at 11 to receive the end of a chain ball and longitudinally slotted at 12 to permit the travel of the usual chain link 13 therethrough to the end bearing aperture 14 of the attachment. The cylindrical body, 10, is formed from a blank of spring sheet metal of substantially 55 rectangular shape with rounding ends, as shown in Fig. 4, the opposite ends of the blank having bays, *a*, cut out on the axial line and the opposite sides of said blank being recessed on the transverse axis whereby when the said sides and ends are rolled to form the completed article, the end bays 60 form the end apertures, 14, and the side recesses form the central opening 11, and the transverse sides of the blank coöperate to 65 form the restricted slot, 12, leading from the end to the central aperture. The aperture 14 of the body 10 is of less diameter than that of the standard chain ball 15 and the rounded end of the cylindrical body 10 70 conforms substantially to the curvature of the ball 15. In normal condition the slot 75 12 is practically closed as shown in Figs. 1 and 2. During the adjustment of the chain end however, the movement of the link 13 80 through the slot 12 spreads the metal until the link reaches the end perforation 14, whereupon the slot automatically closes through the spring action of the metal and the ball is thus prevented from accidental 85 escape from the attachment. The entry of the link into the slot may be facilitated by forming the entry aperture 11 with a guide-way 16 which leads from the aperture to 90 the slot 12.

Various modifications of this attachment will readily suggest themselves and the constructions shown may be regarded merely as exemplary embodiments of my invention.

I claim as my invention:

A chain connector of the type described, comprising a blank formed of spring sheet metal of substantially rectangular shape with rounding ends, the opposite ends of the blank having bays cut out on the axial line and the opposite sides of said blank being recessed on the transverse axis where-

by when the said sides and ends are rolled to form the completed article, the end bays form end apertures and the side recesses form a central opening and the transverse sides of the blank coöperate to form a restricted passageway from said end openings to said central opening.

In testimony whereof I have signed my name to this specification, in the presence of two subscribing witnesses.

GILBERT W. GOODRIDGE.
